UNITED STATES PATENT OFFICE.

ANDREW L. WEIS, OF MONROE, MICHIGAN, ASSIGNOR TO WEIS-VAN WORMER COMPANY, A CORPORATION OF MICHIGAN.

DESIGN FOR A PAPER CLOSURE OR STOPPER FOR PAPER VESSELS.

42,519.

Specification for Design.

Patented May 14, 1912.

Application filed September 16, 1911. Serial No. 649,765. Term of patent 14 years.

To all whom it may concern:

Be it known that I, ANDREW L. WEIS, a citizen of the United States, residing at Monroe, in the county of Monroe and State of Michigan, have invented a new, original, and ornamental Design for Paper Closures or Stoppers for Paper Vessels, of which the following is a specification, reference being had to the accompanying drawing, forming part thereof.

Figure 1 is a top plan view showing the interior of a stopper embodying my new design, and Fig. 2, a bottom perspective view.

I claim:

The ornamental design for a paper closure or stopper for paper vessels, as shown.

ANDREW L. WEIS.

Witnesses:

GEORGE K. DENTEL,
ALBERT G. WUEST.
